UNITED STATES PATENT OFFICE.

EDWIN V. BLANKENSHIP, OF BOZEMAN, MONTANA.

ICE HOUSE.

Application filed January 29, 1923. Serial No. 615,721.

To all whom it may concern:

Be it known that I, EDWIN V. BLANKENSHIP, a citizen of the United States, residing at Bozeman, in the county of Gallatin and State of Montana, have invented a new and useful Ice House, of which the following is a specification.

This invention relates to building construction, and more particularly to a building especially designed for storing and housing ice.

The primary object of the invention is to provide a building adapted to receive ice which has been made by subjecting water converted into a fine spray, to the cold atmosphere.

Another object of the invention is to provide novel means for compensating for the expansion of the ice caused by the freezing of the fluid.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view disclosing a building constructed in accordance with the present invention.

Figure 2 is a sectional view taken on line 2-2 of Figure 1.

Figure 3 is a sectional view taken on line 3-3 of Figure 2.

Referring to the drawings in detail, the building may be of any desired formation and includes outer walls 5, inner side walls 6 and inner end walls 7, the walls 6 and 7 being spaced from the walls 5 to permit of movement of the walls 6 and 7 with respect to the walls 5.

Disposed in the space between the walls 5, 6 and 7 are coiled springs 8 which are secured in position in any desired manner, the coiled springs being arranged in vertical spaced relation with each other to support the walls 6 and 7 throughout the lengths thereof.

The walls 6 and 7 are secured together by means of the angle irons 9 disposed at points adjacent to the side edges of the

walls 6 and 7, each angle iron being formed with an elongated opening 10 designed to accommodate the bolt 11 associated therewith, so that the walls 6 and 7 may move with respect to each other. 60

These angle irons 9 are also arranged in vertical spaced relation with each other in order that the walls connected thereby will be held vertically throughout their lengths, 65 and insure a proper freezing of the ice. To further insure against lateral movement of the walls 6 and 7, plates 9' are provided, the plates being formed with elongated openings to accommodate the bolts 10' that are carried by the vertical bars 11', secured to the walls 5, 6 and 7. Due to this construction, it is obvious that movement of the walls 6 and 7 with respect to the outer walls 5, will be permitted. 70

Partitioning members 12 are arranged within the walls 6 and 7 and extend throughout the height of the building providing compartments 13 to receive the frozen spray to form the same into uniform blocks. 75

In each corner of the building and arranged between the compartments formed by the inner walls 6 and 7 are the vertically disposed boards 14 which prevent lateral movement of the walls 6 and 7 but provide 80 guideways between which the walls 6 and 7 may move to compensate for the expansion of the ice.

A suitable cover not shown may be provided for the building, the cover being however, of the removable type wherein when the building becomes filled with ice, the cover may be readily positioned. The reference character 15 designates a pipe which may have communication with the tank 16 95 which supplies the pipe 15 with fluid, the nozzle 17 which is arranged on one end of the pipe 15 being designed to break the water into a fine spray at a point above the upper end of the building, so that the spray 100 will readily freeze and fall into the compartments formed within the building.

In the use of the system, it is to be understood that a building should be located in a freezing zone so that the fluid may be readily frozen in a manner as described. 105

While I have shown and described the nozzle 17 as fed to a pipe which is in communication with a tank, it is to be understood that the pipe may be in communication with any suitable source of fluid supply. It might be further stated that suit- 110

able doors not shown, may be made a part of the building structure whereby the ice may be readily removed therefrom.

What is claimed is:—

- 5 1. In a building construction, outer walls, inner walls spaced from the outer walls, means disposed between the inner walls and outer walls to secure the inner walls in spaced relation with the outer walls but permit movement of the inner walls towards and away from the outer walls, and means for connecting the inner walls.
- 10 2. In a building construction, outer walls, inner walls spaced from the outer walls,

angle irons connecting the inner walls, said angle irons having slots, bolts carried by the inner walls and extending through the slots to permit of movement of the inner walls with respect to each other, and means for holding the outer walls in spaced relation with the inner walls.

In testimony that I claim the foregoing as my own, I have hereto affixed my signature in the presence of two witnesses.

EDWIN V. BLANKENSHIP.
